UNITED STATES PATENT OFFICE.

BURNHAM C. STICKNEY, OF RUTHERFORD, NEW JERSEY.

INTERNAL-COMBUSTION ENGINE.

Application filed October 31, 1923. Serial No. 671,853.

This invention relates to rotary valve mechanism for internal combustion and other engines.

It is sought to produce an organization which minimizes or avoids the objections which are usually found in rotary valves, including friction and binding and seizing of the valve, which may be due to unsupported pressure at the explosion stroke, or to unequal heating and expansion of the valve and its seat, or other causes.

Another feature is the provision of improved means for quickly opening and quickly closing intake and exhaust ports in combustion chamber and valve chest, and to provide for a much enlarged capacity of the ports as compared with those usual in rotary valve engines.

Another feature is in the nature of an improved organization whereby the speed of the valve may be reduced, to minimize friction, while the valve retains its full capacity.

Another feature is the provision of improved means for cooling the valve and seat; another feature relates to the general construction of the engine head; and still another feature relates to an improved mounting for the spark plug.

The improvement is in the nature of a shutter comprising complementary oppositely-revolving ported shells or elements, one fitted within the other to form a composite shutter or valve, which fits around the cylindrical wall of a valve seat or ported explosion chamber; said composite shutter or valve also fitting within a ported casing or valve chest. The intake and exhaust ports of both the seat and the chest are all controlled by the one composite valve.

The valve completes one cycle of movements for each two cycles of the engine; that is, each valve element revolves once for each four revolutions of the crank-shaft.

The organization includes opposite intake ports in the valve seat, and also opposite exhaust ports. Each valve shell has two intake ports and two exhaust ports; and all of the ports are timed so that the charge is admitted at both sides of the valve chest simultaneously from two manifolds; and all of the exhaust ports in each set are opened simultaneously to discharge into manifolds. During one half of a revolution the composite valve operates for intake, compres-

sion, explosion and exhaust; and during the second half of the revolution it repeats said operations.

Owing to the duplication of the intake ports, each one may be made of half normal size, and the same is true of the exhaust ports. The ports in the valve seat are made as small as possible consistently with other requirements, in order to reduce the pressure and heat of the exploding gas upon the inner valve. The valve is pressure balanced, the intake ports being diametrically opposite from each other in the valve seat, and the same being true of the exhaust ports. Preferably the intake in each side of the inner valve shell is in vertical alignment with its exhaust port, so as to leave large unperforated body portions of the shell for withstanding the shock of explosion. As the intake and exhaust ports are preferably in vertical alignment in the valve shell, the intake port may immediately follow the exhaust port in the valve seat, as will presently be explained.

The composite valve has the characteristic of automatically expanding and contracting its intake and exhaust ports. The intake port in the valve seat is opened by the shutter-like expansion of the composite intake port in the valve, and it is closed by the shutter-like contraction of said composite intake port; and the exhaust port in the seat is thereupon opened by the expansion of the exhaust port in the composite valve, and then closed by the contraction of said composite exhaust port in the valve.

The expansion and contraction of the composite valve ports are rapid. Moreover, the valve seat ports may be made of double the angular extent usual in single-shell rotary valves. All of the advantages of balanced pressure, rapid opening and closing and great capacity of the combustion chamber ports, are thus secured by a single simple organization.

Friction, binding and seizing are minimized or eliminated, by overcoming the unequal heating and expansion of the composite valve and its mounting. The valve seat or explosion chamber, around which the valve fits, is hollow walled, and water is circulated therein from the engine head and thence to the usual radiator, so that overheating of the composite valve is avoided,

and hence the parts of said valve may be closely fitted together and to the stationary ported members. Since the water flows between the inner walls of the explosion chamber and the composite valve, the latter is but little exposed to heat, and its temperature may therefore be kept moderate by contact with the cooled walls of the valve seat and valve chest. The latter is preferably integral with the seat, an annular well being formed between them in which the composite valve rotates.

The water preferably is admitted from the engine jacket to a water space in the detachable engine head, and from this space the water passes in divided streams upwardly between the walls of the hollow valve seats and across over the tops of said seats and then downwardly between the walls, to a water course provided on the opposite side of the engine head, and thence to the radiator; although, if desired, the direction of water may be reversed, passing it first through the valve seats, then through the water-jackets of the engine cylinders and thence through the radiator.

The detachable head of the engine comprises preferably a hollow or box-like base forming a water-jacket, which is in communication with the water-jacket or jackets of the engine block, and is also in communication through the hollow walls of the explosion chambers with the radiator, thus securing uniformly low heat of the valves and associated parts for the various engine cylinders. A feature of the invention is the use of a single casting for the detachable engine head, the row of valve chests, the dome-like valve seats within said chests forming the explosion chambers, and preferably also the intake and exhaust manifolds between which the row of valve chests extends; each valve chest opening into the manifolds on its opposite sides.

Other features and advantages will hereinafter appear.

In the accompanying drawings or diagrams,

Figure 1 is a sectional front elevation taken through the engine cylinder, engine head, valve and valve seat.

Figure 2 is a perspective diagram of the inner valve shell.

Figure 3 is a sectional plan taken through the upper portion of the valve chest.

Figure 4 is a perspective diagram of the outer valve shell.

Figure 5 is a part-sectional bottom view of the engine head and the valve chests, the valves being omitted.

Figure 6 is a longitudinal part-sectional elevation, showing the engine cylinders, engine head, valve chests, valves, manifolds, etc.

Figure 7 is a sectional plan taken through

the upper portions of the valve chests and the intake manifolds.

Figure 8 is a sectional plan taken through the lower portions of the valve chests and the exhaust manifolds.

Figures 9 to 12 are diagrams, showing the various positions or movements of the shells which compose a single valve. Figures 9 and 10 show the intake ports (at the upper portion of the valve), and Figures 11 and 12 show the exhaust ports (at the lower portion of the same valve). Figure 9 shows the positions of the parts at the beginnings of the two cycles of movement that are completed at each revolution of the valve. Figure 10 shows the corresponding positions at the midway points of the piston strokes. Figure 11 corresponds with Figure 9, except that Figure 11 shows the exhaust ports; and Figure 12 corresponds with Figure 10, except that it also shows the exhaust ports.

A conventional engine block comprises a multiplicity of vertical cylinders 20 and a water-jacket 21, each cylinder containing the usual piston (not shown). Upon the cylinder block there may be attached, as by bolts 22, an engine head 23 comprising in its base portion separated water spaces or courses 24, 25 overlying the cylinder block. This base portion of the engine head is a box-like structure extending the length of the engine head. The water space 24 communicates by passages 26 with water spaces 27 in the engine block, so that the cooling water which is pumped into the engine block may flow up through the passages 26 into the engine head, on its way back to the radiator.

Preferably cast integral with the engine head 23 is a series of erect ported domes forming valve seats 28, each containing a combustion chamber (oblong in cross-section) which may comprise upper and lower portions 29 and 30; the upper portion being closed at its upper end by a top plate at 31, and the lower portion being opened at its lower end into the engine cylinder; there being one complete combustion chamber (or gas conduit) for each cylinder.

Fitted around each of the cylindrical valve seats 28 is a pair of oppositely rotating turret-like ported complementary valve portions in the form of interior and exterior nested shells 32, 33. The inner shell or valve portion 32 fits closely to the surface of the cylindrical valve seat 28, and the outer valve portion or shell 33 fits closely around said inner shell 32. The outer valve shell 33 also fits closely within a ported enclosure, housing, casing or chest 34, which may be of cylindrical inner contour and of any suitable exterior form. Neither of these revolving shells by itself serves as a complete valve, but each works co-operatively with the other to open the fixed ports and then to

close them. Any port of the explosion chamber may be closed partly by one shell and partly by the other. The oppositely rotating shells are therefore complementary to one to the other, making a single complete rotary valve which is inserted like a shutter between the ported valve seat and the ported valve chest. The complete valve therefore is in the nature of a pressure-balanced revolving shutter fitting between the fixed ported outer and inner walls of the chest, and having automatically expanding and contracting ports for rapidly opening and rapidly closing the double-size or capacious inner and outer fixed ports. Owing to such port expansion and contraction, each fixed port in chest and chamber is opened or closed at twice the angular speed of either valve shell. The complementary shells fit down in a ported annular well 35, which is formed in the general casting, Figures 1 and 6.

The complementary valve shells preferably form inverted cups or tubes nested together closely within the other. Certain features of the invention may be practiced by using forms other than cylindrical for the nested valve shells surrounding the explosion chamber within the valve chest; but, where cylinders are employed, they may comprise disk-like tops 36 and 37 integral respectively with the valve shells. These tops may serve to support the shells and prevent the lower gas-tight edges thereof from wearing away; and they may also aid in preventing leakage, and also serve to connect the valve shells with bearing hubs 38, 39 of relatively small diameters.

Each of the valve shells makes one revolution to each four revolutions of the crank-shaft, and for this purpose the shells in each pair may be connected up to rotate in opposite directions by means of any suitable gear train, as, for example, by the use of sprocket chains 40, 41 connected to the crank-shaft (not shown) and running over sprocket wheels 42, 43 on shafts 44, 45, the latter extending along the set of valve chests. These shafts 44 and 45 may each make one revolution to two revolutions of the crank-shaft. Shaft 44 may carry helical pinions 46 to mesh with helical gears 47 on the outer valve shells 33, and shaft 45 may carry helical pinions 48 to mesh with gears 49 on the hubs 39 of the inner shells 32; whereby each valve shell may make two revolutions to each revolution of the associated pinion shaft.

The inner shell 32 is provided, preferably at its upper portion, with diametrically opposite intake ports 50, 51; and the outer or companion shell 33 is provided with corresponding intake ports 52, 53. These four ports 50 to 53 open at the same time to admit the charge to opposite valve-seat ports 54, 55, which form continuations of ducts 56,

57 extending from intake manifolds 58, 59 on opposite sides of the row of valve chests. The ports may all be limited in angular extent, inasmuch as they all open simultaneously. The speed of valve opening and closing is rapid, notwithstanding the desirable slow revolution of each valve shell. The composite valve moves from closed position to wide open position in $\frac{1}{8}$ of a revolution of the crank shaft. Thus the valve is wide open at about midway position of the piston.

At its lower portions each inner valve shell is provided with opposite exhaust ports 60, 61, and each outer valve shell with opposite exhaust ports 62, 63; the exhaust ports being suitably timed for a 4-cycle engine. In the inner shell the exhaust ports at each side may be in vertical alignment with the intake ports, while in the outer shell the exhaust ports may be separated by 90 degrees from the intake ports. The cylindrical valve seat has opposite exhaust ports 64, 65, beneath its intake ports, and preferably separated 45 degrees therefrom, although, if desired, they may be in vertical alignment therewith, provided the ports in the valve shells be correspondingly placed or timed. The ports 64, 65 are continuations of ducts 66, 67 leading to opposite manifolds 68, 69, between which the row of valve chests extends. The manifolds at each side are preferably contiguous, for heating the charge, and the exhaust manifolds are preferably well separated from the valve chests to avoid overheating the latter. It is not essential that the inner valve shells revolve all in the same direction, so long as they revolve oppositely from the outer valve shells.

Each port in the engine head may be about 45 or less degrees in extent, and the same may be true of each port in each valve shell. The valve-shell ports are illustrated as each about 45 degrees in extent. The exhaust ports 64, 65 immediately precede the intake ports 54, 55 around the valve seat. When the following edges of the exhaust ports 60, 61, 62, 63 in the oppositely revolving valve shell approach and finally reach the middle of the opposite exhaust ports 64, 65 in the valve seat (thereby co-operatively shutting the same), the leading edges of the intake ports 50, 51 begin to separate from the leading edges of intake ports 52, 53, and hence co-operate in the manner of shutters to open the intake ports 54, 55 in the valve seat or explosion chamber. Thus the closing of each explosion-chamber port occurs at the middle line thereof by the co-operation of the complementary inner and outer valve shells or shutters, and simultaneously the opening of the intake ports in the explosion chamber may begin at the middle lines thereof, by the co-operation of said valve shells.

At Figure 3 there are shown diagrammati-

cally the positions of the valve shells about midway of the intake stroke of the piston, the intake ports being fully open. The inner shell 32 is turning to the right while the outer shell 33 is turning to the left, so that the ports will be closed by movement of each shell to an extent of $22\frac{1}{2}$ degrees, at which time the leading edges of ports 50, 51 will coincide with or overlap the leading edges of ports 52, 53. In this view, it will be understood that the exhaust ports in the inner shell 32 (moving to the right) have just passed the exhaust ports 64, 65 in the valve seat; and exhaust ports 62, 63 in the outer shell 33 (moving to the left) have also just passed said valve seat ports.

In the diagrammatic plan at Figure 7, the line of upstanding valve chests 34 is shown in section through the fixed intake ports 54, 55. The four chests are marked A, B, C, D. At A the intake ports 54, 55 are closed by the body or sides of the inner valve shell 32. In each of the engine cylinders it will be understood that the pistons are supposed to be about midway of their strokes; the piston associated with chest A being midway of its explosion stroke.

The piston associated with chest B is understood to be about midway of its compression stroke. In this the inlet ports 54, 55 are closed.

In chest C the ports 54, 55 are also closed, the piston being midway of the exhaust stroke; the order of firing being A, B, D, C.

In chest D all of the intake ports are fully open, the piston being midway of its intake stroke.

Figure 8 also shows diagrammatically a plan of the chests A, B, C, D, in a section taken through the exhaust ports 64, 65. The valve shells are here seen in the same positions as in the upper row of chests. The upper row thus shows the intake ports, and the lower row the exhaust ports of the same valve shells and chests. In the lower row it will be seen that at A, B and D the exhaust ports 64, 65 are closed, while at C all of the exhaust ports are open: exhaust taking place through chest C while chest D is taking in a new charge.

Figure 9 shows diagrammatically successive positions of the intake ports 50, 51 and 52, 53 in the oppositely revolving inner and outer valve shells or elements 32, 33. The stationary explosion chamber or valve seat is indicated at 28, oppositely ported at 54, 55. There are shown successively in the first four diagrams (while each valve shell makes one-half of a revolution) the positions of the same valve shells at the beginnings of the piston strokes for intake, compression, explosion and exhaust. In every case the intake ports 54, 55 are closed; said ports being shown as about to be opened at the first diagram in this figure, and as having just

closed in the second diagram, and as remaining closed in the next two diagrams. At this stage the shells have each made half of a revolution. In the next four diagrams the operation is similar, the shells each completing one revolution.

In Figure 10 the positions of the same revolving valve shells or elements correspond with those at Figure 9, except that in Figure 10 the valve elements are shown in the positions that they occupy when the piston is midway of its respective strokes. The valve-seat intake ports 54, 55 are fully opened in the first and fifth diagrams, and closed in the remaining diagrams.

In all of Figures 9 to 12, the same complementary valve shells are shown, Figures 9 and 10 showing the intake ports in said shells, and Figures 11 and 12 showing the exhaust ports in the same shells. Figures 11 and 12 also show the exhaust ports 64, 65 in the same valve seat 28 that is seen at Figures 9 and 10. Said exhaust ports are shown at Figure 11 (which shows positions at the beginnings of the strokes of the piston) as always closed; the oppositely revolving valve shells 32 and 33 having just reached their closing positions in the first and fifth diagrams, and being just about to open said ports 64, 65 in the fourth and eighth diagrams.

In Figure 12 the positions of the parts are the same as at Figure 11, except that Figure 12 shows the valve shells midway of the respective strokes of the piston; the exhaust ports of the valve seat 28 being fully opened in the fourth and eighth diagrams and closed in the remaining diagrams.

To balance the pressure upon the inner valve shell 32, which sustains the shock of explosion, the seat ports 50, 51 are placed diametrically opposite each other, and the same is true of seat ports 64, 65. This avoids the tendency of the pressure upon the valve caused by compression and explosion to cause friction between the valve shell 32 and adjacent parts. Moreover, as best seen at Figure 2, the lower ports 60, 61 in the shell may preferably occupy the same angular position as the upper ports 50, 51 therein, so as to avoid undue weakening of the shell, that is, to permit considerable side areas thereof between the ports to remain in unperforated condition, whereby they are fitted to withstand the shocks; these incut portions being, moreover, preferably connected by ribs 70 that are left in the shell between upper and lower ports.

This shell is also stiffened at its lower end by an integral complete ring 71. The outer valve shell 33 is flush with the exterior of said ring, 33 being correspondingly shorter than 32, and said ring filling the bottom of the well 35. The shell 32 is stiffened at its upper portion by the integral disk or

cap 36, preferably integral with the shell, and also by the upper unperforated portion 32^a of the shell, which extends much higher than the valves. The shell is further stiffened by the integral hub portion 38 extending above said cap 36.

Each of the valve seats may be hollow to provide water spaces 72, 73. Each of these water spaces may be bounded partly by the tubular body portion of the valve seat or dome, and partly by transverse internal walls 74, 75. The latter define a diametrical passage which connects the ports 54, 55 in the upper portion of said valve seat.

15 In the lower portion of said valve seat the lateral water spaces are bounded by walls 76, which form a diametrical passage directly connecting the ports 64, 65 in said valve seat. These upper and lower gas passages are in open communication, forming a single explosion chamber, Figure 3; and the lower gas passage terminates at the bottom of the engine head and opens directly at 30 into the engine cylinder 20. These walls, passages and water spaces may be otherwise formed within the scope of the invention. For example, the ports 54, 55 might be placed in vertical alignment with the ports 64, 65 in the valve seat, whereby the transverse gas passages would also be made to coincide, making a straight explosion chamber; but, by following the preferred arrangement, shown at Figure 3, it becomes practicable to have the upper and lower ports in vertical alignment in the outer shell at Figure 2, which is a more desirable construction for sustaining the shock of explosion, without incurring the necessity of unduly increasing the thickness of the shell 32.

40 The water spaces 72, 73 extend the full height of each valve seat or dome, and each is open at its bottom, while at its top each water space is in communication with the other above the top plate 31 of the tubular or dome-like valve seat. Means is provided for causing the water in space 24 to flow up through one water space in the dome and down through the other water space to the water passage 25 on its way to the radiator. In order to secure this circulation, the water spaces at one side of the engine may be partitioned off from the engine head by means of a plate 77, of suitable contour, secured to the bottom of the engine head by screws 78, Figure 5; while the water space 27 on the other side of the engine is open through passages 26 into the general water course 24 in the engine head. From 24 the water flows up through each of the water spaces 73 and across through the annular water space 78^a surmounting the valve seat or dome, and then down through the opposite water space 72 into the water course 25, and thence through outlet 79 to the radiator.

The water courses 24 and 25 may be kept out of independent communication with each other by any suitable means, which will permit the described circulation of the water preferably by the use of suitable integral partitions 80, Figure 5, connecting the valve chests, and integral partitions 81 extending from the end valve chests to the adjoining end walls 82 of the engine head box 23. Thus the water may flow in several streams 75 from the water course 24 into the water course 25, and the valve seats are cooled and overheating of the valve shells is also prevented.

Thus the combustion chamber 28, 74, 75, 80 76 may be formed with a water-jacket arranged interiorly of the valve; that is, the chamber may be double-walled and double-topped, forming the described water spaces, all of which are in open communication with 85 the main water space in the engine head. Thus the water passing up from the engine block may flow along the engine head, and pass up and then down through the hollow-walled combustion chamber, and escape 90 through the outlet 79, whereby the valve seats are protected from exposure to flame and are kept relatively cool; the difference of temperature and hence the extent of relative expansion of the inner and outer revolving shells, as well as of the valve seats and the valve chests 34, being minimized or 95 practically eliminated, so that liability of binding or friction of the nested complementary valve shells may be reduced to a negligible point.

A spark plug 83 may be screwed into a central hollow boss 84, rising from the valve seat or dome, its central compartment or opening extending into the explosion chamber; this boss being cooled by the water, and the sparks being formed in the upper part of the explosion chamber, which forms the path of the incoming charge of fuel, which at this point is mixed but little, or not at all, 100 with the residuum of the previously exploded charge, thus favoring ignition.

The boss 84 may serve as a bearing for the hub 38 of the inner valve shell; and said hub 38 may serve as a bearing for the hub 115 39 of the outer valve shell. The operating gears fixed to these valve shells may be located about in the planes of said hubs, so that the shells may be driven with a minimum of friction.

120 A single plate 86, integral with the engine head may serve for the tops of the water courses 24, 25 (or the top of the engine head), and for the bottoms of the exhaust manifolds 68, 69; and an integral plate 87 may form 125 the tops of the intake manifolds 58, 59, and the tops 31 of the valve seats, and may also serve as the floor of a gear box, the latter also comprising sides 88 and ends 89, which have bearings for the shafts 44, 45. 130

One of the advantages of the invention, as to certain of its features, is that a single inexpensive and compact casting may include the double-walled combustion chambers 28, 74, 75, 76, the valve chests or castings 34, and the hollow or box-like engine head 23, as well as intake manifolds 58, 59 and exhaust manifolds 68, 69; the line of upstanding valve chests 34 extending between these manifolds, which have passages to the opposite sides of the valve chests. Each combustion chamber, although of relatively large exterior diameter, may still accommodate a valve of relatively small diameter, as compared with the engine cylinder. It will be seen that the composite valve may turn in stationary bearings, and may be simple, light and inexpensive, and capable of being readily assembled and disassembled; and the bearings as well as the valve shells themselves may be closely and smoothly fitted and inexpensive. All of the inlet and exhaust ports may be of relatively large capacity, giving maximum efficiency to the engine, while the length of the crank-shaft need be no greater than called for by the engine cylinders, which may be of small diameter and closely packed. Instead of a single casting, the device may be made of several parts if desired.

The inner of the tubular walls 28 of the valve seat may rise in the form of an oblong column 99 directly from the floor plate 99 of the engine head, that is, from disk-like portions 100 integral with the floor plate and forming bases for said valve seats and opening into the explosion chambers at 30. The valve chests 34 may rise from the top plate 86 of the engine head, the spaces between said tubular walls 28 and the chests 34, together with the annular spaces 101 above the valve seats, forming water courses, which open from the course 24 and deliver into the course 25.

The annular water space 101 is formed by an extension 102 of the valve seat or dome 32, said extension having a cap 103, and having the central compartment 85 containing spark plug 83, and opening at the bottom into the explosion chamber or gas passage.

Oil may be provided from any suitable source, entering through a pipe 90 having outlets 91, from which the oil may drop upon the hubs of the gears 49, and may flow into passages 92 formed in the boss 84, said passages extending downwardly and then radially of the boss at 95 to the exteriors of the valve seats, whereby the latter are lubricated. The supply of oil may be sufficient to cause it to accumulate in the bottom of the gear box, and from thence it may flow inwardly through passages 96 in the valve chests, to lubricate the exteriors of the shells 33; and it may also flow through passages 97 in said shells, to lubricate their interiors.

Any other suitable lubricating means may be provided. The gear box may be provided with a pair of covers 98, resting upon the top of the box, and each separately removable without disturbing the spark plugs, which extend up between said covers.

To guard against loss of compression, the inner valve shell 32 may be pressed downwardly by means of a leaf spring 105, secured at one end upon the gear 49, and at its free end pressing upwardly in a circumferential groove 106 formed in the stationary boss 84, so that there is a constant downward spring pressure, causing the bottom of the valve ring 71 to press down upon the bottom of the well 35, making it gas tight. The spring may play in a vertical groove 107 in the hub of the gear. As a further guard against loss, the bottom surface of the ring 71 may be formed with any suitable number of grooves 108, of which three are shown, these grooves being annular or extending all around the ring; and the bottom of the well 35 may be formed with upstanding annular ribs 109, fitting closely in the grooves.

An advantage is derived by making the diameter of the valve shells so great, as shown at Figure 3, that the surface travel of each shell is greater, during $\frac{1}{8}$ of its revolution, than the width of the port in the valve seat, whereby the valve port is more promptly opened, and may remain open a longer time, and be more promptly closed.

Variations may be resorted to within the scope of the invention, and portions of the improvements may be used without others.

Having thus described my invention, I claim:

1. The combination with a ported explosion chamber or valve seat, of complementary ported shells fitted one within the other to form a composite valve fitting around said valve seat, and means for continuously revolving said shells in opposite directions, said composite valve ported coordinately with the porting in said seat to form two complete cycles of operations during each complete revolution of the valve, each shell being connected to make one revolution for each four revolutions of the engine-crank-shaft, the valve seat having diametrically opposite intake ports and also diametrically opposite exhaust ports, said intake ports being in a different zone from the exhaust ports in each shell and in said valve seat.

2. The combination with a ported explosion chamber or valve seat, of complementary ported shells fitted one within the other to form a composite valve fitting around said valve seat, and means for continuously revolving said shells in opposite directions, said composite valve ported coordinately with the porting in said seat to form two complete cycles of operations during each complete revolution of the valve,

- each shell being connected to make one revolution for each four revolutions of the engine-crank-shaft, the valve seat having diametrically opposite intake ports and also diametrically opposite exhaust ports, the latter immediately in advance of the former, and the inner shell having its exhaust ports substantially in alignment with its respective intake ports.
3. The combination with a ported explosion chamber or valve seat having intake and exhaust ports, of complementary ported shells fitted one within the other to form a composite valve fitting around said valve seat, and means for continuously revolving said shells in opposite directions, said composite valve ported coordinately with the porting in the seat to form two complete cycles of operations during each complete revolution of the valve, each shell being connected to make one revolution for each four revolutions of the engine-crank-shaft, said intake ports being in a different zone from the exhaust ports in each shell and in said valve seat, the intake ports being diametrically opposite in the inner shell, the exhaust ports being also diametrically opposite in the inner shell and respectively in vertical alignment with the intake ports, the intake ports in the outer shell being directly opposite each other, and the exhaust ports in the outer shell being also directly opposite each other but separated by about 90 degrees from the intake ports, and the intake ports in the valve seat being directly opposite each other but separated by about 45 degrees from the adjacent exhaust ports.
4. The combination with an engine head having an explosion chamber or valve seat having ports, of complementary ported shells fitted one within the other to form a composite valve fitting around said explosion chamber, and means for continuously revolving said shells relatively to each other, the porting in said seat and valve being coordinated, said engine head having water spaces, and said valve seat or explosion chamber having hollow walls in bottom communication with said water spaces, and a water space above said valve seat in communication with said hollow walls, means, including upward and downward channels, being provided for causing water or cooling fluid to flow upwardly at one side of the valve seat and across the top thereof and downwardly at the other side of said valve seat.
5. The combination of a detachable engine head having a row of hollow walled ported explosion chambers or valve seats, each valve seat having ports, complementary ported shells fitted one within the other to form a valve fitted upon each valve seat, and means to revolve the shells differentially, the porting in said valve being coordinated with the porting in said seat, said engine head partitioned to form a water course at each side thereof, one of said water courses in the engine head being in bottom communication with the hollow wall at one side of each valve seat, the other water course being in bottom communication with the hollow wall at the other side of each valve seat, said hollow walls forming separate water channels in communication with each other above said ported valve seats.
6. The combination of an engine head having a row of channeled hollow walled ported explosion chambers or valve seats, each valve seat having ports, a shell valve fitted upon each valve seat, means to revolve the valve, said engine head partitioned to form a water course at each side thereof, one of said water courses in the engine head being in open communication with the channel in the hollow walls at one side of each valve seat, the other water course being in open communication with the channel in the hollow walls at the other side of each valve seat, said channels forming water spaces in communication with each other above said ported valve seats, one of said side channels being in bottom communication with the water jacket of the engine cylinders, and a plate partitioning the water course at the other side of the engine head from the water jacket of said engine cylinder.
7. The combination of an engine head having a row of hollow walled ported explosion chambers or valve seats, each valve seat having ports, a shell valve fitted upon each valve seat, and means to revolve the valves, said engine head partitioned to form a water course at each side thereof, said hollow walls forming separated water channels jacketing the opposite sides of each valve seat, and a water space over the top of each valve seat, communicating at the top with both of said channels, whereby the cooling fluid may flow up one side of the valve seat and across the top thereof and down the other side, one of said water courses in the engine head being in bottom communication with the channel at one side of each valve seat, the other water course being in bottom communication with the channel at the other side of each valve seat.
8. The combination of an engine head having a row of hollow walled ported explosion chambers or valve seats, each valve seat having ports, a shell valve fitted upon each valve seat, and means to revolve the valves, said engine head partitioned to form a water course at each side thereof, said hollow walls forming separated water channels jacketing the opposite sides of each valve seat, and a water space over the top of each valve seat, communicating at the top with both of said channels, whereby the cooling fluid may flow

- up one side of the valve seat and across the top thereof and down the other side, one of said water courses in the engine head being in bottom communication with the channel at one side of each valve seat, the other water course being in bottom communication with the channel at the other side of each valve seat, all of the water spaces in said valve seat being enclosed by the valve.
9. The combination with a detachable engine head having a series of valve seats, each having ports, of a shell valve fitting around each valve seat, means for revolving said valves, chests within which said valves are fitted, each chest having intake and exhaust ports, the ports in each valve coordinated with the ports in its seat and chest, each valve seat being hollow walled, means being provided for causing the water in the engine head to pass in divided streams upwardly between the hollow walls of all the valve seats and across over the tops of said seats, and downwardly between the hollow walls of said seats to a separate water compartment provided in the engine head.
10. The combination with a detachable engine head having a series of valve seats, each having ports, of a shell valve fitting around each valve seat, means for revolving said valves, chests within which said valves are fitted, each chest having intake and exhaust ports, the ports in each valve coordinated with the ports in its seat and chest, each valve seat being hollow walled, means being provided for causing the water in the engine head to pass in divided streams upwardly between the hollow walls of all the valve seats and across over the tops of said seats, and downwardly between the hollow walls of said seats to a separate water compartment provided in the engine head.
11. The combination with a detachable engine head having a series of valve seats, each having ports, of a shell valve fitting around each valve seat, means for revolving said valves, chests within which said valves are fitted, each chest having intake and exhaust ports, the ports in each valve coordinated with the ports in its seat and chest, each valve seat being hollow walled, means being provided for causing the water in the engine head to pass in divided streams upwardly between the hollow walls of all the valve seats and across over the tops of said seats, and downwardly between the hollow walls of said seats to a separate water compartment provided in the engine head, and a single casting comprising the detachable engine head, the valve chests, the hollow-walled and hollow-topped valve seats, and the water courses in the engine head.
12. The combination with an explosion chamber or valve seat having ports, of complementary ported shells fitted one within the other to form a composite valve fitting around said valve seat, and means for continuously revolving said shells in opposite directions, said composite valve ported co-ordinately with said seat to form two complete cycles of operations during each complete revolution of the valve, the inner shell being connected to make one revolution for each four revolutions of the engine-crank-shaft, the intake ports in said valve seat being placed above the exhaust ports therein, and the outer shell being connected for rotation relatively to the inner shell.
13. The combination of an engine head

ing intake manifolds, one at each side of the row of valve chests, and exhaust manifolds, one at each side of the row of valve chests.

12. The combination with a detachable engine head having a series of valve seats, each having ports, of a shell valve fitting around each valve seat, means for revolving said valves, chests within which said valves are fitted, each chest having intake and exhaust ports, the ports in each valve coordinated with the ports in its seat and chest, each valve seat being hollow walled, means being provided for causing the water in the engine head to pass in divided streams upwardly between the hollow walls of all the valve seats and across over the tops of said seats, and downwardly between the hollow walls of said seats to a separate water compartment provided in the engine head, and a single casting comprising the detachable engine head, the valve chests, the hollow-walled and hollow-topped valve seats, and the water courses in the engine head, and also comprising intake manifolds, one at each side of the row of valve chests, and exhaust manifolds, one at each side of the row of valve chests, and also comprising a gear-box surmounting the row of valve chests.

13. The combination of an engine head having a row of hollow-walled ported valve seats, each valve seat having ports, a ported shell valve fitted upon each valve seat, and means to revolve the valves, said engine head partitioned to form separate water courses, said hollow walls forming separated water channels for each valve seat, a water space over the top of each valve seat forming a communication from one of said channels to the other, whereby the cooling fluid may flow up one side of the valve seat and across the top thereof and down the other side, one of said water courses in the engine head being in open communication with a channel of each valve seat, the other water course being in open communication with the other channel of each valve seat, and a spark plug passing down through the top water space of each seat.

14. The combination with an explosion chamber or valve seat having ports, of complementary ported shells fitted one within the other to form a composite valve fitting around said valve seat, and means for continuously revolving said shells in opposite directions, said composite valve ported co-ordinately with said seat to form two complete cycles of operations during each complete revolution of the valve, the inner shell being connected to make one revolution for each four revolutions of the engine-crank-shaft, the intake ports in said valve seat being placed above the exhaust ports therein, and the outer shell being connected for rotation relatively to the inner shell.

15. The combination of an engine head

having a row of hollow walled ported valve seats, complementary ported shells fitted one within the other to form a valve fitted upon each valve seat and coordinated thereto, and means to revolve the shells differentially, said engine head partitioned to form a water course at each side thereof, said water courses in open communication with the hollow walls of said valve seats, said hollow walls forming water spaces in communication with each other above said ported valve seats, the inner valve shell extending up to surround the water space above said ported valve seat and having an integral 15 stiffening ring at its bottom edge.

16. The combination with an explosion chamber or valve seat having intake and exhaust ports, of complementary ported shells fitted one within the other to form a composite valve fitting around said valve seat and coordinated thereto, said valve seat having its ports arranged in upper and lower tiers, each port or passage extending transversely through the seat, the walls of 25 said valve seat between the ports being hollow to form water spaces, a water space above said valve seat to communicate with said water spaces therein, and means to effect relative rotation of said valve shells.

17. The combination with an explosion chamber or valve seat having upper intake ports and lower exhaust ports, of complementary ported shells fitted one within the other to form a composite valve fitting 30 around said valve seat and coordinated thereto, means for continuously revolving said shells in opposite directions, said composite valve ported to form two complete cycles of operations during each complete 35 revolution of the valve, each shell being connected to make one revolution for each four revolutions of the engine-crank-shaft, a cross passage forming said intake ports in the upper part of the valve seat, and a cross 40 passage forming said exhaust ports in the lower part of the valve seat, said passages together forming a continuous gas passage or explosion chamber opening down into the engine cylinder.

18. The combination with an explosion chamber or valve seat having upper intake ports and lower exhaust ports, of complementary ported shells fitted one within the other to form a composite valve fitting 45 around said valve seat and coordinated thereto, and means for continuously revolving said shells in opposite directions, said composite valve ported to form two complete cycles of operations during each complete 50 revolution of the valve, each shell being connected to make one revolution for each four revolutions of the engine-crank-shaft, a cross passage forming said intake ports in the upper part of the valve seat, a cross 55 passage forming said exhaust ports

in the lower part of the valve seat, said passages together forming a continuous gas passage or explosion chamber opening down into the engine cylinder, the walls of said valve seat between the passages being hollow to form water spaces, and a water space being provided above said valve seat to communicate with said water spaces therein. 70

19. The combination with an explosion chamber or valve seat having upper intake ports and lower exhaust ports, of complementary ported shells fitted one within the other to form a composite valve fitting around said valve seat and coordinated thereto, means for continuously revolving 75 said shells in opposite directions, said composite valve ported to form two complete cycles of operations during each complete revolution of the valve, each shell being connected to make one revolution for each four revolutions of the engine-crank-shaft, a cross passage forming said intake ports in the upper part of the valve seat, and a cross passage forming said exhaust ports in the lower part of the valve seat, said passages together forming a continuous gas passage or explosion chamber opening down into the engine cylinder, said valve seat having hollow walls at the sides of said passages to 80 form water spaces, and also having a water space surmounting said passages and in communication with the side water spaces. 85

20. The combination with a detachable engine head having a series of ported valve seats, of a series of shell valves fitting around said seats and ported coordinately therewith, means for revolving said valves, chests within which said valves are fitted, each chest having intake and exhaust ports coordinated with the valve and seat, said valve seats being hollow walled, a water space being provided in the engine head, and means to cause the water therefrom to pass in divided streams upwardly between hollow walls of all the valve seats and across over the tops of said seats, and then downwardly between hollow walls of said seats to a water compartment provided in the engine head, a single casting comprising the detachable engine head, the valve chests, the hollow-walled and hollow-topped valve seats, and the water courses in the engine head, and also comprising intake manifolds, one at each side of the row of valve chests, and exhaust manifolds, one at each side of the row of valve chests. 100 105 110 115

21. The combination with a detachable engine head having a series of ported valve seats, of a series of shell valves fitting around said seats and ported coordinately therewith, means for revolving said valves, chests within which said valves are fitted, each chest having intake and exhaust ports coordinated with the valve and seat, said valve seats being hollow-walled, a water space being 120 125 129

- ing provided in the engine head, means to cause the water therefrom to pass in divided streams upwardly between hollow walls of all the valve seats and across over the tops of said seats, and then downwardly between hollow walls of said seats to a water compartment provided in the engine head, a single casting comprising the detachable engine head, the valve chests, the hollow-walled and hollow-topped valve seats, and the water courses in the engine head, and also comprising intake manifolds, one at each side of the row of valve chests, and exhaust manifolds, one at each side of the row of valve chests, a single plate integral with the engine head serving for the tops of the water courses therein and for the bottoms of the exhaust manifolds, and a single integral plate forming the tops of the intake manifolds and the tops of the valve seats.

22. The combination with an engine head having an explosion chamber or valve seat having ports, of a ported shell-valve fitting around said explosion chamber, and means for revolving said valve, the porting in said seat and valve being coordinated, said engine head having water spaces, and said valve seat or explosion chamber having hollow walls in bottom communication with said water spaces, and a water space above said valve seat in communication with said hollow walls, means, including upward and downward channels, being provided for causing water or cooling fluid to flow upwardly at one side of the valve seat and across the top thereof and downwardly at the other side of said valve seat.

23. The combination of a detachable engine head having a row of hollow-walled ported explosion chambers or valve seats, each valve seat having ports, a ported shell-valve fitted upon each valve seat, and means to revolve the valves, the porting in said valve being coordinated with the porting in said seat, said engine head partitioned to form a water course at each side thereof, said water courses in bottom communication with the hollow walls of said valve seats,

said hollow walls forming water spaces in communication with each other above said ported valve seats.

24. The combination of a detachable engine head having a row of hollow-walled ported explosion chambers or valve seats, each valve seat having ports, a ported shell-valve fitted upon each valve seat, and means to revolve the valves, the porting in said valve being coordinated with the porting in said seat, said engine head partitioned to form a water course at each side thereof, one of said water courses in the engine head being in bottom communication with the hollow wall at one side of each valve seat, the other water course being in bottom communication with the hollow wall at the other side of each valve seat, said hollow walls forming separate water channels in communication with each other above said ported valve seats.

25. The combination with an engine head having an individual water jacket, of a valve seat in said head having intake and exhaust ports, a ported shell-valve surrounding said seat, means for rotating said valve, and a chest within which said valve is fitted, said chest having intake and exhaust ports coordinated with the ports in the seat and valve, said seat being hollow-walled, and provision being made for circulation of cooling fluid to and fro therethrough from one point to another point in said water jacket, separate inflow and outflow, communications being open between said jacket and the hollow of said wall.

26. The combination of a row of ported valve seats, shell-valves surrounding said seats and ported in coordination therewith, means to rotate said valves, and means for cooling said valve seats, comprising an engine head upon which said valve seats are carried, said engine head having water courses, and means for passing the water in divided streams from one water course up within the valve seats and across the same and down to the other water course.

BURNHAM C. STICKNEY.
